UNITED STATES PATENT OFFICE.

FRANK PASTOR, OF AKRON, OHIO.

CHANGEABLE SIGN.

1,203,126.

Specification of Letters Patent. Patented Oct. 31, 1916.

Application filed February 16, 1916. Serial No. 78,617.

To all whom it may concern:

Be it known that I, FRANK PASTOR, a subject of the King of Hungary, residing at Akron, in the county of Summit and State 5 of Ohio, have invented new and useful Improvements in Changeable Signs, of which the following is a specification.

This invention relates to improvements in signs and particularly to that type in which 10 a multiplicity of different names, designating articles may be combined with a variety of prices and quantities.

The principal object of the invention is to provide a sign of extreme simplicity, such 15 as can be readily used by grocery men and others without difficulty and without occupying an excessive amount of space.

The second object is to provide a device 20 susceptible of indicating the names of an unlimited variety of articles upon one part thereof, the second part also changeable relating to the price, and a third part indicating the quantity, by weight, measure or count, to which the price refers.

25 These and other objects are attained by the novel construction and combination of parts hereafter described and shown in the accompanying drawing, forming a material part of this specification, and in which:—

30 Figure 1 is a perspective view of the device, resting upon a convenient support and indicating the purpose of the invention. Fig. 2 is a vertical section, taken substantially through a center line of the same.

35 Fig. 3 is a plan view of one of the main changeable plates. Fig. 4 is a similar plan view, showing the changeable plate used to indicate the nature of the article. Fig. 5 is a plan view, showing an interchangeable 40 card, relating to the quantity indicated by the article and price arranged in connection thereof.

The structure is comprised of a plurality 45 of polygonal plates 10, through the center of which is an opening 11, adapted to receive the bolt 12, the head 14 of which is engaged with the back of a card holder 15, adapted to be disposed against the surface of the outer plate and held tightly thereagainst by 50 means of the thumb-nut 16, which presses against the spring washer 17, as shown in Fig. 2. Next adjacent to the washer 17 is a plate element 20 formed with an integral

hinge 21 and a supporting element 22, disposed in the manner of an easel so that its 55 lower edge rests upon the same surface as that of the lower angular edge of the plate.

The outermost or front plate is formed with an angular recess 25, and may have upon its surface one or more indexing characters as the hands 26. Upon the face, near the edge of the plates 10 and central with the angular edge, may be printed any preferred designation, as a price, or combination of 60 prices and quantity, both sides of the plates 65 being used so that in a device having five plates, it is possible to display eighty different characters.

In the card receiver, 15, a plurality of rectangular small cards may be used having on 70 their exterior designations, as lb., doz., each, etc., while larger cards 30 may have upon their surface the names of the articles to which it is desired to call attention, such a card being clearly indicated in Fig. 4. 75

In operation, the larger card 30 is intended to be inserted between the plates 10, preferably between the second and third, in such manner as to permit the selected name to appear, the plate immediately in front being 80 so turned as to show the rate or price at which the article will be sold, according to the quantity indicated on the smaller card. When the plates have been turned so as to show the desired figure, they are securely 85 clamped by means of the wing nut 16. Should the desired price not appear upon the face of the second plate, but is found on any of the succeeding plates, upon either side thereof, the nut 16 is removed, the 90 structure separated and the proper plate placed next adjacent to the front plate, whereupon it is again assembled.

Thus it will be seen that a very simple device is presented susceptible of a wide range 95 of indications as to material, prices and quantities and that the combinations which can be made to appear are limited only by the number of plates and cards employed.

Having thus described my invention, what 100 I claim as new and desire to secure by Letters Patent is:—

In a changeable sign structure, the combination with a plurality of polygonal plates bearing inscriptions upon each side thereof, 105 contiguous to their outer edges, a cover plate

having an aperture through which any selected inscription can be seen, a card holder arranged on the front of said cover plate, an easel support at the rear of said structure, 5 a bolt securing said card holder, plates and easel together, said bolt having a wing nut, resilient means interposed between said easel

and said nut, and a plurality of elements bearing inscriptions upon each side adapted to be received in said card holder.

In testimony whereof I have signed my name to this specification.

FRANK PASTOR.
